OSKAR GRAUHEDING, OF DUSSELDORF, GERMANY, ASSIGNOR TO RHEINISCHE METALLWAAREN- UND MASCHINENFABRIK, OF DUSSELDORF- DERENDORF, GERMANY, A CORPORATION OF GERMANY.

TELESCOPE GUN-SIGHT.

1,127,230.

Specification of Letters Patent.

Patented Feb. 2, 1915.

Application filed June 5, 1913. Serial No. 772,018.

To all whom it may concern:

Be it known that I, OSKAR GRAUHEDING, engineer, a subject of the German Emperor, residing at 26 Fischerstrasse, Dusseldorf, 5 Germany, have invented certain new and useful Improvements in Telescope Gun-Sights; and I do hereby declare the following to be a full, clear, and exact description of the invention, such as will enable others 10 skilled in the art to which it appertains to make and use the same.

Various sighting devices have been proposed for guns in which the correct elevation is shown for any given quadrant angle 15 by means of curves or curved guides.

As is well known, the angle of elevation must decrease as the quadrant angle increases and must vanish for all ranges at a quadrant angle of 90°.

20 According to the present invention, which is designed for use with guns for shooting at targets lying in any height above the gun, as for instance, air ships and the like, the correct sighting point for any range and quadrant angle is shown in the field of view 25 of the telescope by a very simple construction.

Referring to the drawings, Figure 1 shows 30 a side view of the construction of a telescope according to the invention, parts being in section. Fig. 2 is a rear view of the telescope. Fig. 3 shows the movable range plate on which are the curves connecting the range 35 and angle of elevation with quadrant angles for both elevated and depressed targets. Fig. 4 shows a plate with similar curves either for elevated or depressed targets, but not for both. Fig. 5 shows the disposition of the curves adapted for a straight line 40 movement of the curve plate. Fig. 6 is a view in side elevation of a modified form, parts being in section. Fig. 7 is a face view. Fig. 8 is a side view opposite to that shown in Fig. 6, with parts broken away. Figs. 9 45 and 10 are face views of the range plates showing modified forms of markings.

In the telescope 1 (Fig. 1) there is a movable glass plate 2 which is held in a support 3 having teeth on its outer edge with which 50 engage the teeth of a pinion 4, the support and the plate 2 being rotatable relatively to a fixed glass plate 6 by means of a screw head 5. On the fixed glass plate 6 there is a vertical line (Fig. 3).

A plurality of range curves are plotted on 55 the rotatable glass plate 2 and on the periphery of the plate are the quadrant angle graduations indicating the several angles of site for elevated and depressed targets. It will be seen that when the quadrant angle 60 is zero there is the greatest distance between the range divisions which are marked 0, 4, 8, 12, 16 and 20, corresponding to ranges of 0, 400, 800, 1200, 1600, and 2000 meters. The marking is repeated every 10°. If the target 65 lies in such a height that the angle of site is 40° then the plate 2 is turned so that the mark 40° will be covered by the vertical line on the plate 6. If, for instance, the distance of the target is 1600 meters, the target 70 must be covered by the point of intersection between the vertical line of the plate 6 and between the range curve 16 drawn on the glass plate 2. It will be seen that this point of intersection lies somewhat higher than if 75 the plate 2 were not turned, or only moved for an angle of 10°. As the quadrant angle increases the distance between the range divisions continually decreases, until at 90° it vanishes, that is, all the range curves meet 80 in a point as the angle between the line of sight and the axis of the barrel is zero for all ranges if the target lies in a vertical direction above the gun. The quadrant angle can be given by order in degrees, and set by 85 the gun layer by observation of the target.

Fig. 4 shows the construction of the curves relating to either elevated or depressed targets. As shown in this figure, there is but one group of curves which extend only in one direction from the vertical line of the plate 6 in the position of the plate 2 corresponding to an angle of site of zero. In this arrangement it is assumed 90 that the angle between the line of sight and the axis of the barrel is for the same range of the same size notwithstanding the target is lying above or below the gun. If great exactness is required, for instance when firing from air ships on targets lying below or 95 on targets lying above the firing air ship, it will be preferable to have two groups of range curves as shown in Fig. 3, one of said groups serving for targets lying above the gun and the other for targets lying below 100 the gun. With this arrangement, if the angle of site is positive the plate 2 is turned to the left, while if it is negative the plate 105

is turned to the right. If the quadrant angle is not given by order, it can be known from the spirit level 7 which is rotated by the worm 8 together with the range plate 2, 5 until it is leveled. The quadrant angle can also be shown by a pendulum 9, by the movement of the barrel or by the elevating gear. If a straight line movement of the range plate is desired, the range curves must 10 be plotted in rectilinear coördinates, as shown in Fig. 5, in which the quadrant angles are set out as abscissæ and the ranges as ordinates.

Figs. 6 to 10 show a construction in which 15 the curves are arranged so as to always intersect with the fixed vertical straight line. The sighting point is determined by the intersection of the curves drawn as described in Letters Patent No. 1,004,416, dated September 26, 1911, connecting the angles of elevation and the quadrant angles.

In Figs. 9 and 10 the numbers on the edge 20 of the disk or plate 11 do not mark the angles of site, but the ranges, and for each 25 of such ranges there are small curves for correcting the angle between the line of sight and the axis of the barrel according to the angle of site. In Fig. 9 there is only one curve for each range, while in Fig. 10 30 are shown two groups for each range, this arrangement insuring exactness for positive and negative angles of site.

In the form shown in Figs. 9 and 10, a glass disk 11, on which are indicated range 35 divisions from 400 to 2000 meters, is fixed to a member 12 supported in the telescope housing 10, the member 12 being designed to be rotated by a hand wheel 13 to adjust the plate or disk 11 according to the range 40 scale on the edge thereof. The setting of the range is effected against the resistance of a locking device 14, comprising a spring-pressed pin having a rounded head for taking in one of a series of depressions 45 arranged in the support, 12, the depressions corresponding to the range divisions on the disk 11. The spindle of the support 12 and also the locking device are journaled in a toothed ring 16, which can be rotated by a 50 worm 17 (Figs. 7 and 8), the turning of the ring also effecting movement of the disk 11 relatively to a fixed plate 18 having a vertical line thereon.

In the use of the device shown in Figs. 55 6 to 10, the disk 11 is rotated by means of the hand wheel 13 to effect adjustment according to the range scale on the edge of the disk. Then the toothed ring 16 is turned by the worm 17 according to the angle of 60 site, the necessary movement of the ring 16

being controlled by the scale shown in the upper part of Fig. 7, reaching from zero to 90°. Then the vertical line of the stationary disk 18 meets the small curve of the adjusted range in a different point, according to the adjusted angle of site. Only one curve intersects the vertical line at any time. Therefore there is only one sighting point and any chance of error is excluded. It will be seen that all the curves ultimately touch 70 the zero circle.

If the quadrant angle is not given by order, it can be obtained by a spirit level 19 rotated by the worm 20 together with the toothed ring 16 and range disk 11 until it is 75 leveled. The curves connecting the quadrant angles with the angles of elevation can also be adapted to show the sighting points, if the glass plate is moved in a straight line.

On the same general principle the lateral 80 deviation can be allowed for according to the angle of elevation when aiming at elevating targets, if corresponding curves are caused to intersect with a horizontal line. Also if a range finder for balloons is used 85 the decrease in the angle of elevation as the quadrant angle increases can be shown in the field of view of the telescope. The telescope can also be employed in a suitable manner for determining the quadrant angle. 90

I claim as my invention:

1. In combination with a telescope gun sight for aiming at elevated or depressed targets, a plate having a fixed mark, and a transparent plate designed to be moved in 95 the focal plane of said telescope relatively to such fixed mark, said plate having a plurality of curves thereon, the points of intersection of said curves with the fixed mark varying as said plate is set to the quadrant 100 angle.

2. In combination with a telescope gun sight for aiming at elevated or depressed targets, a plate having a fixed mark, and a rotary transparent plate designed to be 105 moved in the focal plane of said telescope relatively to such fixed mark, said plate having a plurality of separate curves plotted for different ranges, the intersection of said curves with the fixed mark varying 110 as said plate is rotated to the quadrant angle.

In testimony whereof, I have signed this specification in the presence of two subscribing witnesses.

OSKAR GRAUHEDING. [L.S.]
